UNITED STATES PATENT OFFICE

2,469,254

EAR TRUMPET, INCLUDING ADJUSTABLE SECTIONS

Severin B. Bankson, San Francisco, Calif.

Application January 15, 1946, Serial No. 641,269

2 Claims. (Cl. 181—25)

1

The accompanying drawings illustrate, and the specification which is to follow pretty clearly describes and explains the use and application of one embodiment of the invention, an object of which is the provision of means through which the hearing of a person may be greatly amplified.

Another object of the invention is to provide means whereby the resonance of sounds may be conducted directly into the orifice of the ear of a user.

Another object of the invention is to provide an adjustable sound reflecting ear-piece.

A further object of this invention is to provide a substantially invisible ear engaging sound amplifier.

Other features and advantages will become more readily apparent from the following description and the accompanying illustrative drawings in which:

Figure 1 is a perspective view of the invention.

Figure 2 is another perspective view of the device.

Figure 3 is a sectional view taken on line 3—3 of Figure 2, and

Figure 4 is a similar view taken on line 4—4 of Figure 2.

While one embodiment of the invention is illustrated in the above referred to drawings, it is to be understood that they are merely for the purpose of illustration and that various changes in construction may be resorted to in the course of manufacture in order that the invention may be utilized to the best advantage according to circumstances which may arise, without in any way departing from the spirit and intention of the device, which is to be limited only in accordance with the appended claims. And while there is stated the primary field of utility of the invention it remains obvious that it may be employed in any other capacity wherein it may be found applicable.

In the accompanying drawings, and in the following specification, the same reference characters are used to designate the same parts and elements throughout and in which 10 refers to the invention and 11 indicates one member and 12, another member of the device and each of which are in the form of shells and each having side walls 12' and 12'', substantially semi-cylindrical top, rear and bottom walls, 14, 15 and 16, and open in front. The side walls 12' and 12'' have cut-outs which together form a C-shaped rim 17, adapted to fit closely around the ear of a user.

The side wall edge 18, of member 11, is pro-

2

vided with a returned flange 19, into which the edge 20, of member 13'', is slidable and the said latter member being telescopically mountable within the member 11. The walls 13' and 13'', of said members 11 and 12, are each corrugated as at 23 and 24, which corrugations interlock to hold the said members 11 and 12 into adjusted position whereby the device may be contracted or extended to fit ears of various sizes. The walls 13' and 13'' are offset from the said semi-cylindrical walls 14, 15 and 16, to form a sounding board for directing sound passing into the shell into the orifice of the ear of a user.

The above described device is to be formed of relatively thin transparent plastic in order that it may be worn without being detectable by other persons and it is to be so positioned upon the ears that the lower end 25 seats back of the ear lobe in order not to interfere with pendant jewelry. In this connection, the said end 25 may be foreshortened or formed in a plane inward of that of the upper end 26. Sound directed toward the front of the device will be amplified and resonated into the ear.

From the foregoing specification it will become apparent that the invention disclosed will adequately accomplish the functions for which it has been designed and in an economical manner and that its simplicity, accuracy and ease of operation are such as to provide a relatively inexpensive device considering what it will accomplish and that it will find an important place in the art to which it appertains when once placed on the market.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described the invention, that which is claimed to be new and desired to be procured by Letters Patent is:

1. An acoustic device comprising a pair of outer ear enclosing shell members forming a resonant chamber, each member including a substantially rectangular plate, two contiguous margins of each of said plates being bent over to form a curved channel for enclosing a portion of the outer ear, said channels slidably interfitting each other and maintaining said shell members in

frictional contact, means on the plates for locking the same in selected adjusted positions relative to each other, and another margin of one of said plates bent over to form a channel and engaging a corresponding margin of the other plate to maintain the said shell members in slidable engagement.

2. The combination of claim 1 wherein said means includes a plurality of corrugations on each of said plates.

SEVERIN B. BANKSON.
